UNITED STATES PATENT OFFICE

110,791

DESIGN FOR A CHAIR OR SIMILAR ARTICLE

Aileen Armour, Los Angeles, Calif.

Application May 10, 1938, Serial No. 77,096

Term of patent 14 years

To all whom it may concern:

Be it known that I, Aileen Armour, a citizen of the United States, residing in the county of Los Angeles and State of California, have invented a new, original, and ornamental Design for a Chair or Similar Article, of which the following is a specification, reference being had to the accompanying drawings, forming part thereof.

Fig. 1 is a rear perspective view of the chair or similar article showing my design in closed position with a corner portion of the cover fabric elevated to show the table top therebeneath.

Fig. 2 is a similar view showing my chair or similar article with the closure members open.

Fig. 3 is a front perspective view.

The characteristic feature of the design resides in the rear back rest portion of the chair, as shown.

I claim:

The ornamental design for a chair or similar article, as shown and described.

AILEEN ARMOUR.
